UNITED STATES PATENT OFFICE.

SAMUEL W. RUSHMORE, OF PLAINFIELD, NEW JERSEY.

RADIATOR FOR AUTOMOBILES.

Application filed September 18, 1921. Serial No. 500,382.

To all to whom it may concern:

Be it known that I, SAMUEL W. RUSHMORE, a citizen of the United States, and resident of Plainfield, in the county of Union and State of New Jersey, have invented certain new and useful Improvements in Radiators for Automobiles, of which the following is a specification.

My present invention is shown as embodied in an air cooled radiator suitable for use in connection with the cooling systems of internal combustion engines used on automobiles, trucks, flying machines, etc. Certain features of the invention are useful when the radiator is employed in the usual way to cool down-flowing water, discharged into the top and removed from the bottom thereof, but they are especially useful when the radiator is utilized as an upflow steam condenser operated in accordance with method described in my Patent 1,378,724, granted May 17th, 1921. It will be evident, however, that various features of the invention may be employed for other purposes and in other relations.

In the standard types of radiators now used on automobiles and trucks, either operated by the down-flow water cooling method or the up-flow steam-condensing method, the central part of the radiator is much more effective for cooling than the side portions because the fan for drawing the air through the honeycomb, is relatively ineffective for creating draft through the side portions of the honeycomb.

In view of the above, my invention contemplates making the vertical flow paths at the sides of the honeycomb longer than the paths at the center, thereby exposing the water to the action of a much greater cooling area at the sides.

Another way is to make the flow resistance at the sides greater than at the center. This may be accomplished either by making the passages at the sides of smaller flow section, or, as in the preferred embodiment of my invention, increase of length of the side paths will give increased flow-resistance combined with increased distance of flow. In the preferred form, zigzagging the paths at the sides to make them longer, also increases the flow resistance.

It will be evident that my above described invention is of vastly increased importance where the honeycomb is peaked in at the top, thus making the vertical height of the

honeycomb much less at the sides than at the center.

The above and other features of my invention may be more fully understood in the following description in connection with the accompanying drawings, in which:

Fig. 1 is a diagrammatic view indicating the relations of the up and down flow passages at the center and the sides; 65

Fig. 2 is a section on the line 2—2, Fig. 1;

Fig. 3 is an enlarged sectional view showing the construction of the honeycomb which is diagrammatically indicated in Fig. 70 1; and

Fig. 4 is a similarly enlarged face view of a honeycomb element as viewed from the right in Fig. 3.

In these drawings, the radiator casing 75 comprises a peripheral casing 1, front and rear walls 2, 3, in which the honeycomb is soldered to form a water tight container. The central portion of the honeycomb at 4 is of greater height than the side portions 5 80 and their constructions are different.

The central portion 4 is shown as comprising a plurality of strips bent so as to form a vertical wall 5 with transverse fins 6. A similar strip with similarly spaced fins 85 is assembled in the manner shown in Fig. 3 so that its vertical walls 5^a and bent fins 6^a in conjunction with walls 5 and fins 6 on the other strip, form a vertically aligned series of through air passages 7. As indicated in Fig. 4, the strips 5, 5^a, have out-bent marginal bearing surfaces 8, 8, which space apart the surfaces 5, 5^a, to form the vertical flow paths for the water or steam to be cooled. There are also co-operating fore-and-aft rib portions 9, 9, arranged to interlock and maintain vertical registry. These elements assembled as shown in Fig. 3 have the edges dipped in molten tin or solder to hold the parts together and make the vertical passage 90 tight.

The side portions of the honeycomb are formed by pairs of reversely bent strips 10, 11, nested as shown to form the zigzag passages 12. These pairs of strips are held in spaced relation by marginal bent portions similar to the portions 8, 8, described in connection with the central part of the honeycomb structure. A plurality of the assembled strips 11, 10, are associated as 105 shown in the drawings so that the outwardly projecting surfaces of strips 10 form the

third side for the in-bent portion of an adjacent strip 11 and vice versa.

Obviously the flow path between each pair of strips 10, 11, is twice as long as the straight flow path between 5 and 5^a. Thus the flow resistance at the sides, other things being equal, will be twice as great as for the central portion, and the time taken for flow of the fluid medium through a given vertical distance at the sides will be twice as long as at the center. Obviously, the flow sections of vertical passages 5, 5^a, need not be the same as those between 10 and 11, nor is it necessary that the air passages formed by the strips 10, 11, be of the same width and height as the width and height of the air passages 5, 5^a. Hence by suitable variation the lengths and resistances of the up-and-down flow paths at the sides may be made to bear any desired relations to the lengths and resistances of the central paths. In this way it is possible to design the side areas with reference to the center areas so that the cooling at the sides will be approximately the same as at the center when water is used as a cooling medium. Or, when the device is used as a steam condenser, the height of honeycomb which will come into operation as actual condensing surface, will be the same for the sides as for the center.

However, such exact equalizations are by no means necessary for the practice of my invention. Very great improvement is obtained merely by making the flow passages for the sides of greater length or of greater flow resistance than for the center area.

The above described principle of increasing the flow resistance, or the length of the flow path, or both, may be embodied in widely different types of honeycomb structure; nor is it always necessary to combine two types of structure to get the desired result. For instance, both features can be combined in the through-tube type of honeycomb, such, for instance, as is shown in my application, Serial Number 500,381, filed

September 13, 1921. By using larger tubes at the sides, or setting them closer together, or giving a polygonal cross-section to body portions of the tubes, the flow path length and the flow-resistance of the air passages and the interspaces can be varied within quite wide limits.

An upper inlet 13 may be employed for down-flow water cooling; or a lower inlet 14 for the up-flow steam-condensing method, the outlet 15 being usable in either case.

I claim:

1. An air cooled radiator having low resistance flow paths for the cooling fluid over the central portions of the area of the honeycomb and higher individual flow resistance for each of the paths at the side portions of said area.

2. An air cooled radiator having the flow paths for the cooling medium longer at the sides than for the central portions area thereof.

3. An air cooled radiator having a honeycomb with vertical paths for the flow of fluid to be cooled through the central portions of the radiator, and zigzag paths for the side portions of the radiator.

4. An air cooling radiator of the type in which the vertical height of the honeycomb is substantially less at the sides than at the central portion, the flow passages at the sides being designed for greater flow resistance per unit of vertical height than are the flow paths for the central portion.

5. An air cooling radiator of the type in which the vertical height of the honeycomb is substantially less at the sides than at the central portion, the flow passages at the sides being designed to have flow paths at the sides of length equal to or greater than the flow paths for the central portion.

Signed at Plainfield in the county of Union and State of New Jersey this 10th day of September A. D. 1921.

SAMUEL W. RUSHMORE.
